DESIGN FOR AN EYESHIELD OR SIMILAR ARTICLE

William A. Mendelsohn, Chicago, Ill.

Application August 9, 1947, Serial No. 140,792

Term of patent 14 years

(Cl. D57—1)

To all whom it may concern:

Be it known that I, William A. Mendelsohn, a citizen of the United States residing at city of Chicago, county of Cook, State of Illinois, have invented a new, original and ornamental Design for an EYESHIELD or SIMILAR ARTICLE, of which the following is a specification, reference being made to the accompanying drawing, forming a part thereof, in which Figure 1 is a front perspective view of an eyeshield, showing my new design; and Figure 2 is a perspective view of the underside with the visor element slightly raised from its position in Figure 1.

I claim:

The ornamental design for an eyeshield or similar article, substantially as shown.

WILLIAM A. MENDELSON.
